UNITED STATES PATENT OFFICE

HUMPHREY GEORGE TAYLOR, OF PENN, NEAR WOLVERHAMPTON, ENGLAND

SHIP'S DAVIT

Application filed July 20, 1929, Serial No. 379,750, and in Great Britain November 7, 1928.

This invention relates to ships' davits, and has for its object to provide simple and ready means for launching boats therefrom.

According to this invention, each davit arm is pivoted, by a horizontal and longitudinal pivot axis, to a carriage adapted to travel along a track which is at right angles to the ship's side, and means are provided whereby, during the outward travel, the arm is automatically caused to swing outboard. If it is desired that the carriage shall move out under the force of gravity, the track is inclined downward and outward when the carriage may be controlled by the respective fall; but if the track is substantially horizontal, means must be provided to impel the carriage outboard.

In carrying out the invention, the davit arm has a downward and somewhat forward extension below its pivot axis with the carriage and carries a roller or rollers at its foot which, during the first part of the outward travel of the carriage, runs upon a track, or tracks at a predetermined point in which, or each of which, is formed an opening or pocket to receive the respective roller, whereby the foot of the arm becomes arrested, with the result that further outward movement of the carriage causes the upper end of the arm to swing outboard turning about its pivot axis with the carriage, while the roller or rollers move to some extent within the pocket or pockets.

A convenient embodiment of the invention as applied to a gravity davit is described with reference to the drawings herewith, in which:—

Figure 1 is a view in elevation of the davit as seen from the respective end of the boat, the latter being shown in its inboard position.

Figure 2 is a view of the davit as seen from outboard; and,

Figure 3 is a view corresponding to Figure 1, but showing the boat outboard and in the act of being lowered into the water.

In these drawings:—A is the davit arm pivoted by a horizontal pivot axis B to a carriage C arranged to run on two inclined tracks D D composed of two channels with

their open sides facing each other. The carriage C, at its rear end, has a pair of rollers E E adapted to run upon the under surface of the channels and a second pair F F adapted to run upon the upper surfaces of the channels. At its forward end the carriage has a pair of rollers G G adapted to run upon the upper surfaces of the channels. The davit arm A is continued downwards and somewhat forwards below the pivot axis B and it carries at its lower end a pair of rollers H H adapted to run within the channel D D. J J are openings or pockets in the lower flanges of the channels into which the rollers H H can enter, and they are guided into such pockets by curved walls K. M M are stops on the under surfaces of the channels to limit the forward travel of the rollers E E and consequently of the carriage C outboard. N is the respective fall passing from a winch, not shown, round a pulley P, thence to a pulley Q on the carriage, then upward over a guide pulley R on the carriage and over a pulley S at the head of the davit arm to the shackle T of the boat. a is a catch hook adapted to engage over the pivot pin of the rollers E E to retain the carriage inboard. The hook has a tail b extending inward beyond the pivot axis of the hook and to this tail the gripe c (for securing the boat) is connected so that the carriage cannot be released until the gripe has been cast off.

To launch the boat the gripes are cast off and the catch hook of each davit released. Each carriage is then retained solely by its fall N. On paying out the fall the carriage goes down the tracks by gravity and the rollers H H at the foot of the davit, running in the channels, keep the arm in the same relationship to the carriage until the rollers H H encounter the curved walls K which hold back the foot and cause the arm to swing outboard about its pivot axis B. The movement of the arm is, however, governed by the travel of the carriage and the rollers H H go down into the openings or pockets J which permit of their requisite downward movement. The travel of the carriage is arrested by the rollers E encountering the stops M, and this, of course, also arrests the outward

movement of the davit arm. Further paying out of the fall N simply lowers the boat.

To get a boat inboard, the falls are wound in raising the boat until each shackle T comes against the head of the respective davit arm A, after which the carriage is drawn up the track, and the davit arm swings inboard while the rollers H H, by leaving the openings or pockets and travelling up in the channels, bring the arm to its final position in relation to the carriage and retain it there. At the extreme inner end of the travel of each carriage the catch piece is re-engaged and the gripe replaced.

It will be seen that the davit head has a pair of upwardly and outwardly curved slots d d in which lies a transverse pin e at the top of the shackle, whereby the weight of the boat, at the respective davit, is relieved from the fall when at the inboard position. When the arm H is outboard, the slots slope downward and allow the pin to disengage.

Having fully described my invention what I claim and desire to secure by Letters Patent is:—

1. A ship's davit comprising a track extending to the ship's side, a carriage adapted to run on said track and being held thereagainst at its rearward end, a davit arm pivoted to said carriage by a horizontal pivot axis, a downward extension of said arm below its pivot axis and means whereby the foot of said downward extension is held in relation to the track to cause said arm to swing outboard as said carriage moves outward.

2. A ship's davit comprising a track extending to the ship's side, a carriage adapted to run on said track and being held thereagainst at its rearward end, a davit arm pivoted to said carriage by a horizontal pivot axis, a downward extension of said arm below its pivot axis, a portion of said track in which said foot is guided during the first part of the movement of the carriage and means whereby said foot is arrested in said track during the latter part of the outward movement of said carriage to cause said arm to swing outboard.

3. A ship's davit comprising a track extending to the ship's side, a carriage adapted to run on said track and being held thereagainst at its rearward end, a davit arm pivoted to a said carriage by a horizontal pivot axis, a downward extension of said arm below its pivot axis a roller on the foot of said downward extension guided by a portion of said track and an opening in the bottom of said track portion to allow said roller to enter to arrest said roller and allow movement thereof in a direction normal to the track, as said arm swings outboard.

4. A ship's davit comprising a track extending to the ship's side, a carriage adapted to run on said track and being held

thereagainst at its rearward end, a davit arm pivoted to said carriage by a horizontal pivot axis, a downward extension of said arm below its pivot axis, a roller on the foot of said downward extension guided by a portion of said track, an opening in the bottom of said track portion to allow said roller to enter to arrest such roller and allow movement thereof in a direction normal to the track and a wall placed across said track portion to arrest said roller and guide it into the opening as the said arm swings outboard.

5. A ship's davit comprising a track extending to the ship's side, said track composed of two channels with their open sides facing each other, a carriage adapted to run on said track, rollers of said carriage engaging on the upper surfaces of the upper flanges of said channels, rollers of said carriage engaging on the under surfaces of the lower flanges of said channels, a davit arm pivoted to said carriage by a horizontal pivot axis, an extension of said arm below its pivot axis, rollers mounted on the foot of said extension, and adapted to engage between the flanges of said channels and a recess in the lower flange of each channel each to receive one of said rollers to allow of their movement normal to the track as the arm swings outboard.

In witness whereof I have hereunto signed my name this 5th day of July, 1929.

HUMPHREY GEORGE TAYLOR.
